UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

RAIL-END-SUPPORTING RAIL-JOINT.

1,394,598.

Specification of Letters Patent. Patented Oct. 25, 1921.

Application filed July 7, 1921. Serial No. 483,034.

To all whom it may concern:

Be it known that I, BENJAMIN WOLHAUPTER, a citizen of the United States, residing at New Rochelle, in the county of Westchester and State of New York, have invented certain new and useful Improvements in Rail-End-Supporting Rail-Joints, of which the following is a specification.

This invention relates to an improvement 10 in rail joints providing a hard and substantial support for the rail ends to prevent battering out of the joint, and permitting the use of rolled splice bars of low carbon steel.

15 In the construction of rail joints, particularly of the angle bar type, it is recognized as desirable to use low carbon steel for the rolled splice bars because of the fact that low carbon steel bars will bend under load 20 without fracture or breaking, but nevertheless will permit the flowing of the metal under the ends of the rails. To obviate that defect in the use of low carbon steel bars, the present, and more expensive practice is 25 to make the splice bars of high carbon steel which is heat treated and oil quenched. That process results in the production of a splice bar having hardness and stiffness but at the same time one which is quite suscep- 30 tible, under load and shock, to fracture and breakage.

Accordingly, an important object of the present invention is to provide a rail joint construction which combines the advantages 35 of rail joints made of both low carbon and high carbon steel while at the same time obviating the defects of both. To that end the invention contemplates the use of low carbon steel bars so designed as to support 40 the rail heads throughout the joint except for a relatively small area at and adjacent to the ends of the rails and at such locations to provide substantial rail end supports made of high carbon steel, which supports 45 receive the entire shock and wear of the rail ends and thereby prevent the loosening and battering out of the joint.

Furthermore, the improved construction is so designed as to provide a flexible joint 50 allowing the wave motion of the track to pass through it from rail to rail.

With these and other objects in view, which will be apparent to those familiar with this art, the invention consists in the 55 novel construction, combination and arrange-

ment of parts hereinafter more fully described, illustrated and claimed.

Although susceptible of modification, certain preferred and practical embodiments of the invention are shown in the accompanying drawings, in which—

Figure 1 is a perspective view of the rail joint embodying the improved rail joint construction.

Fig. 2 is a vertical transverse sectional view at the center of the joint.

Fig. 3 is a horizontal sectional view.

Fig. 4 is a view similar to Fig. 3 illustrating the change in the form that may be resorted to in making the supporting shock-piece.

Like references designate corresponding parts in the several figures of the drawings.

The present invention is applicable to any form of rail joint bar, but for illustrative purposes there is shown in the drawings an angle bar type of rail joint. Referring thereto, the numeral 1, designates the splice bar fitting the fishing spaces of the rails "R—R," and in accordance with the present 80 invention it is proposed to make the splice bar of the relatively inexpensive low carbon steel which yields to bending stresses but will not readily fracture or break under the loads and stresses transferred thereto from 85 the rails. The head of this splice bar 1, is intended to contact with the under side of the rail heads throughout the entire joint with the exception of a relatively small area at and adjacent the meeting ends of the rails 90 and at such location, that is at the center part thereof, the splice bar 1 is bull-dozed or otherwise shaped to provide at the inner side thereof, a socket or housing 2, which is adapted to receive a vertically arranged 95 supporting shock-piece 3.

The supporting shock-piece 3, preferably is made of high carbon steel, heat treated and oil quenched, the intent of the invention being to have the shock-piece of very hard 100 metal as compared with the softer metal of the splice bar 1, so as to be able to resist the shock and wear from the rail ends and thereby prevent the loosening and battering out of the joint. As shown in the drawings, the shock-piece 3, is inserted between the splice bar and the rail webs at the center of the joint and is disposed on end in such a manner that it will span the joint between the ends of the rails and will have a bearing 110

contact with the under sides of the heads of both rails and with the upper sides of the base flanges of both rails. Therefore, the shock-piece will receive the load from the 5 end of one rail and transmit it downwardly on top of the base of the adjacent rail, the splice bar proper taking the loads beyond the shock-piece. At the same time, it will have been observed that the construction is 10 such as to render the joint sufficiently flexible to permit the wave motion of the track to pass through it from rail to rail.

The form of the socket or housing 2, may be changed and likewise the shape of the 15 shock-piece varied to suit requirements without departing from the spirit or scope of the invention.

I claim:

1. A rail joint including a fishing bar and 20 a separate shock-piece engaging the under side of the rail head.
2. A rail joint having a relatively soft fishing bar, and a separate relatively hard supporting member engaging the under side 25 of the head of the rail.
3. A rail joint including a fishing bar and a relatively hard supporting shock-piece held by the fishing bar beneath the heads of the rails at the center of the joint.
- 30 4. A rail joint including a fishing bar, and

an upright supporting shock-piece engaging the under sides of the heads and the upper sides of the flanges of both rails.

5. A rail joint including an upright rail-end support engaging beneath the heads and 35 upon the base flanges of both rails.

6. A rail joint including an upright relatively hard supporting shock-piece; the upper and lower ends of which shock-piece respectively engage the under sides of the 40 rail heads and the upper sides of the rail flanges.

7. A rail joint including a bar having a centrally arranged socket and an upright relatively hard supporting shock-piece in- 45 serted in said socket and respectively engaging the rail heads and rail base flanges.

8. A rail joint including a relatively soft fishing bar having a socket and a relatively hard supporting shock-piece inserted in said 50 socket and having its opposite ends respectively engaging with the rail heads and the rail base flanges.

In testimony whereof I hereunto affix my signature in the presence of two witnesses. 55

BENJAMIN WOLHAUPTER.
